OIL TREATMENT DEVICE

Anita Margot Braun, Winnipeg, Manitoba,
CanadaApplication August 18, 1948, Serial No. 44,829
In Canada September 26, 1947

1 Claim. (Cl. 210—150.5)

1

This invention relates to a device for renovating or reclaiming lubricating oil in internal combustion engines.

An object of the invention is to provide a device for insertion in the lubricating oil circuit of an engine and adapted to continuously receive a flow of oil, to filter the received oil, and to remove the readily volatile impurities therein by distributing the oil in a thin film over an extensive heated surface.

The invention will be described with reference to the accompanying drawing, in which

The single figure is a sectional elevation of a device in accordance with the invention.

Referring to the figure, 1 is a cylindrical casing and 2 a cylindrical filter housing concentrically arranged within the casing with its walls in spaced relation to the walls of the casing. As shown, the housing 2 is supported by legs 3 extending upwardly from the bottom wall 4 of casing 1.

A perforated partition 5 is supported on an annular shoulder 6 within the housing 2 and spaced a short distance above the bottom wall of the housing. Thus the space within the latter is divided by the partition into an upper filter chamber 7 of major extent and a lower oil-receiving chamber 8 of minor extent. The chamber 7 is packed with a suitable filtering material 9. Oil from the oil circuit of an engine (not shown) is pumped into chamber 8 through an inlet 10 which extends through the bottom walls of casing 1 and housing 2. Preferably the partition member 5 is provided with an axial open-ended tubular extension 11 extending upwardly for a short distance into the filter chamber. The extension 11 may be perforated as shown.

The top of housing 2 is provided with a perforated closure disc 14 having a convex upper surface and a concave lower surface.

Casing 1 has a restricted axial opening 13 provided with a perforated closure disc 12. A bolt 15 extends through disc 14 and has screw-threaded engagement with disc 12 to hold the closure discs 12 and 14 in place and to maintain the assembled casing and housing in rigid condition. A wingnut 16 on bolt 15 permits ease of assembly and disassembly of the various elements of the structure. An oil outlet 17 is provided in the bottom wall of casing 1, and leads to the crankcase of the engine.

In operation, hot used oil from the engine flows into chamber 8 under pressure from the usual oil pump. The oil flows upwardly through perforated partition 5 and through the filter

material 9 which extracts solid impurities from the oil. As the filtered oil emerges through the perforated upper disc 14, it flows downwardly over the convex upper surface of the disc in substantially complete radial distribution thereover. Since the overall diameter of disc 14 is not greater than the outside diameter of housing 2, as the radially flowing oil leaves the surface of disc 14 it flows downwardly in a thin film on the outer surface of housing 2 in countercurrent flow to hot fumes rising from the hot oil in the engine crankcase through the outlet 17. Since the housing 2 becomes heated by the hot oil flowing through the same, the thin film of oil on the outer surface thereof is subjected to the combined heat of the incoming oil and the hot fumes from the crankcase which vaporizes gasoline, water and other impurities in the oil. The rising fumes entrain the vaporized impurities and emerge to the atmosphere through perforated disc 12. The treated oil flows back to the crankcase through outlet 17. Provision of the thin film of oil over a relatively great area permits a particularly effective heat treatment of the oil.

The device described may be employed in place of or in conjunction with the usual breather cap on the oil-filling pipe of an engine, the outlet 17 being connected to such pipe. Back pressure of the engine is released through perforated disc 12. To refill the crankcase with oil, it is merely necessary to remove disc 12 and pour fresh oil directly into casing 1, from which it may flow through outlet 17 into the crankcase.

What is claimed is:

1. A device for renovating the lubricating oil of an internal combustion engine comprising a vertically disposed casing having circular top and bottom walls and an imperforate cylindrical side wall, said top wall having an axial opening 35 therein and being otherwise imperforate, said opening being substantially smaller than said top wall, a perforated closure disc removably secured in said opening, said bottom wall being provided with upwardly extending feet and having two 40 openings therein and being otherwise imperforate, a filter housing having circular top and bottom walls and an imperforate cylindrical side wall positioned co-axially within said casing and resting on said feet, the walls of said housing being uniformly spaced apart from the corresponding 45 walls of said casing, the top wall of said housing being dome shaped and perforated and of a size not greater than the external size of the cylindrical side wall of said housing, the bottom wall of 50 said housing having an opening therein aligned

with one of the two openings in the bottom wall of said casing and being otherwise imperforate, a perforated circular partition supported within said housing at a substantial distance above the bottom wall thereof, filtering material filling the space within said housing enclosed by said perforated dome shaped top wall, said perforated partition and said imperforate cylindrical side wall, a conduit for oil to be renovated extending upwardly through one of said two openings in the bottom wall of said casing and through said aligned opening in the bottom wall of said housing and opening into the space between the bottom wall of said housing and said perforated partition, and a conduit for hot gases and for

renovated oil communicating with the other of said two openings in the bottom wall of said casing.
